UNITED STATES PATENT OFFICE.

CORNELIUS POELMAN, OF CHICAGO, ILLINOIS.

NUT LOCK.

Application filed July 21, 1928. Serial No. 294,383.

This invention is a nut lock for any conventional form of bolt and nut, and the object is to provide in combination a specially prepared bolt adapted to coact with a specially prepared nut, to the end that the latter may be releasably locked in place upon the threaded end of the bolt.

In the drawing

10 Figure 1 is a an elevation of the assembly; Figure 2 is a longitudinal section through the assembly, the key, the springs and a portion of one end of the bolt being shown in full;

15 Figure 3 is a detail of the key; Figure 4 is a detail of the nut.

In carrying out the invention, I provide a bolt 1 of any conventional form, and slot the threaded stem thereof to form a longitudinal key-way 2. This key-way is continuous, except at the inner end thereof is left a bridge 3, convexed at its inner side as shown at 4, so as to provide a narrow, arcuate key anchoring aperture 5 communicating with the main key-way 2. The outer threaded end of the bolt 1 is provided with two spring sockets 6 in the plane of the key-way 2 and opening thereinto. A key 7 is provided, the same being long and flat and adapted to fit loosely in the key-way 2. This key has a lip 8 adapted to overhang the end face 9 of the bolt, and spring seating recesses 10 adapted to register with the sockets 6 when the key is in place in the key-way 2. The tail 11 of this key is curved to conform with the aperture 5 of the bolt. Coil springs 12 are provided for the sockets 6. The nut 13 is formed with two diametrically opposed slots 14 in the inner peripheral wall of the threaded bore thereof, the said slots being of a width corresponding with the key-way 2.

The elements are assembled by inserting the curved tail 11 of the key 7 within the aperture 5 and laying the stem of the key within the key-way 2. The springs 12 are seated in the sockets 6 and the recesses 10 of the key are seated over the outer ends of these springs. The key 7 is then pressed inwardly against the action of the springs, and the nut 13 is turned onto the end of the bolt. It will be

noted that as the slots 14 successively align 50 with the key 7, the latter will be forced outwardly into that slot, thereby preventing the unturning of the nut, except as the key 7 may be intentionally depressed within the key-way 2 for that purpose. The curved tail 11 of the 55 key 7 serves to retain the key in place within the key-way 2, and the lip 8 of the key serves to hold the key against sliding longitudinally inwardly along the key-way 2. Therefore, the purpose of the lip 8 is both to 60 prevent the inward longitudinal movement of the key 7 and to keep the springs 12 properly aligned with their seating recesses 10. This lip 8 also serves to engage a tool whenever it may be desired to draw out the said 65 key 7 for any purpose.

While I have herein described a certain specific manner and method of constructing and assembling the elements of my invention, it is understood that I may vary from the 70 same in minor details, not departing from the spirit of my invention, so as best to construct a practical device for the purpose intended, as defined in the appended claim.

I claim:

75 In a device of the kind described, the combination of a bolt having a key-way extended out longitudinally through the threaded end, the inner end of the key-way being bridged to form an arcuate key retaining aperture, the 80 said bolt having also spring sockets in its outer threaded end in the plane of the key-way and opening thereinto, a nut having slots upon the inner peripheral wall of its threaded bore adapted to register with the said key-way of the bolt upon the turning of the nut, a key loosely fitted within the said key-way of the bolt, the same having a curved tail for engaging the key retaining aperture of the key-way of the bolt, having recesses adapted 85 to align with the said spring sockets of the bolt, and having a lip adapted to fit over the end face of the bolt, and springs seated within the spring sockets of the bolt and having their outer ends engaged by the recesses in 90 the said key.

95 In testimony whereof I affix my signature.
CORNELIUS POELMAN.
